TRACK HANGER

Russell E. Nelles, South Orange, N. J.

Application December 5, 1934, Serial No. 756,019

11 Claims. (Cl. 104—123)

This invention relates to a new and useful improvement in monorail trackage suspensions, in which a cable or other flexible member is utilized as a means of suspension or supporting connection between a monorail trackage section and its supporting superstructure.

My reference to monorail trackage or to monorail trackage section or sections as above or hereinafter noted applies to any standard or special steel section or sections, hot or cold rolled, or drawn, which may be utilized as a monorail trackage section on which one or more pair of single flanged trolley wheels are made to operate and such sections as may be utilized to constitute crane runways, on which cranes of the underhung type are made to operate.

At present it is common practice to employ individual steel hanger rods or other rolled or drawn steel sections as a means of vertical support or connection between a monorail trackage section and its supporting superstructure with similar supplementary members diagonally placed with respect to the horizontal or inclined plane of the monorail trackage, and parallel or at various angles thereto, to provide lateral and longitudinal support to the monorail trackage. These supplementary members are generally referred to as angle or sway bracing.

An object of my invention is to provide a means of monorail suspension whereby a wide range of vertical, lateral and longitudinal support and adjustment may be obtained between the monorail trackage and its supporting superstructure without resorting to the use of individual steel hanger rods or other rolled or drawn sections for the purpose noted, each of which must necessarily be fabricated to a predetermined length to meet individual existing superstructure conditions.

Another object of my invention is to provide a means of monorail trackage suspension whereby the limit of vertical adjustment between the monorail trackage and its supporting superstructure is not confined to the threaded portion of a supporting hanger rod or other member of suspension or to the threaded portion of a monorail trackage fitting which provides conventional support or connection between the means of suspension and a monorail trackage section.

A further object of my invention is to provide a means of monorail trackage suspension whereby a side pull capacity may be obtained from a trolley operated on a monorail trackage without imposing undue strain to the means of suspension or to component parts of a trolley operating

thereon, by providing for a uniform lateral movement of the monorail trackage section throughout its length, independent of the inherent flexibility of the cable or flexible member means of suspension.

Other objects and advantages of my invention will be apparent from the following description taken in conjunction with the accompanying sheets of drawings which describe and illustrate an embodiment of my flexible member suspension for monorail trackage.

One embodiment of my invention contemplates the use of a cable or other flexible member, continuous or otherwise, composed of ferrous or non ferrous metal, stranded or otherwise fabricated, used in connection with a suitable upper and lower cable or flexible member fitting in a manner described and as illustrated on the accompanying sheets of drawings as a means of suspension or connecting support between a monorail trackage section or monorail trackage section attachment fitting and its supporting superstructure or its supporting superstructure fitting, attached thereto.

Figure 1, on the accompanying sheets of drawings, is a side view or elevation of my flexible member suspension for monorail trackage with upper and lower cable or flexible member fittings with conventional ceiling or supporting superstructure fittings and suitable monorail trackage attachment fittings with provision for vertical adjustment and providing a rigid connection between my means of suspension and a T bar section utilized in this instance as a monorail trackage section.

Figure 2 illustrates a transverse or sectional view of my flexible member suspension taken on line A—A of Figure 1.

Figure 3 is a side view of a modified form of the invention.

Figure 4 is an end view thereof; and

Figure 5 is a plan view thereof somewhat enlarged.

Similar parts in different figures have the same reference numerals.

Numerals 1 indicates a conventional ceiling or supporting superstructure.

Numerals 2 indicates a conventional ceiling or supporting superstructure fitting, attached thereto.

Numerals 3, 4, and 5 indicate component parts of the upper cable or flexible member fitting, hereinafter described in greater detail.

Numerals 6 indicates a cable or other flexible member, continuous or otherwise and composed

of ferrous or non ferrous metal, stranded or otherwise fabricated.

Numerals 7, 8, and 9 indicate component parts of the lower cable or flexible member fitting 5 hereinafter described in greater detail.

Numeral 10 indicates a turnbuckle or other suitable fitting providing for connection with vertical adjustment, between the lower cable or flexible member fitting and the monorail trackage 10 attachment fitting.

Numeral 11 indicates a lock nut therefor.

Numeral 12 indicates a monorail trackage attachment fitting composed of a forked section with extended shank one side of which is provided with a countersunk hole and opposite side with a threaded hole and extended shank is provided with a right hand thread.

Numeral 13 indicates a countersunk-head machine screw, which when assembled with monorail trackage attachment fitting 12, provides a rigid connection between such fitting and the T bar section indicated by numeral 14, in this instance utilized as a monorail trackage section.

A more detailed description of the upper cable 25 or flexible member fitting indicated by numerals 3, 4, and 5 with its functional relationship to cable or flexible member 6 is as follows:

Component part 3 is segmental in shape as shown with extended shank terminating in a ball 30 or oval shaped head providing thereby a universal joint connection to conventional fitting indicated by numeral 2. The segmental portion of component part 3 is provided with a curved recess as indicated for reception of cable or flexible member 6, and at the radius point of the curved recess a threaded hole is provided.

Component part 4 is also segmental in shape and provided with a corresponding curved recess for reception of cable or flexible member 6, 40 and at the radius point of the curved recess a countersunk hole is provided as shown.

Component part 5 is a countersunk-head machine screw which, when tightened provides a rigid connection between the upper cable or flexible member fitting 3, 4, and 5, and the cable or flexible member 6, with provision for slideable adjustment thereon as required.

It will be noted from the above description and with reference to the accompanying sheets of drawings, that while the upper cable or flexible member fitting provides a rigid connection to the upper loop of the cable or flexible member 6 the construction indicated permits the upper loop of the cable or flexible member to swivel about the conventional fitting 2, not only in a horizontal plane, but angularly in all directions as well.

This construction permits the fittings 2, to be located in the same vertical plane with the center line of the monorail trackage as shown or alternately off-set therefrom, thereby providing lateral stability as required to the lower cable or flexible member fittings, indicated by numerals 7, 8, and 9.

Referring to Figures 3, 4, and 5, it will be seen 65 that the fixed superstructure 1 supports a trackage 14 by certain means therein shown, said means consisting of fittings 2 and 3 holding a suspending cable 6, or the like said fitting 2 being arranged in staggered fashion, as shown 70 in Figure 5. It will be noted from Fig. 5 that the fittings 2 which are attached to the superstructure 1 are alternately disposed at opposite sides of the line of trackage indicated by 14. The cable 6 passes over the pulleys 9 which pulleys 75 are held by fittings indicated by reference char-

acter 10 to the member 12. In Figs. 3, 4 and 5 the fittings are generally indicated by 3 and 10 and they can of course be arranged in the manner shown in Figs. 1, 2 and 3 with the parts 3, 4 and 5, and 7 to 11 substituted therefor or similarly acting parts may be utilized. The structure shown in Figs. 3, 4 and 5 arranged in staggered fashion, is also shown in another embodiment in Figs. 1 and 2.

A more detailed description of the lower cable 10 or flexible member fitting indicated by numerals 7, 8 and 9 with its functional relationship to cable or flexible member 6 is as follows:

Component part 7 is a forked section with extended shank as shown, each side of the fork 15 being provided with a hole for machine bolt hereinafter described. The extended shank of the forked section is provided with a left hand thread.

Component part 8 is a machine bolt with nut. 20

Component part 9 is a grooved pulley with suitable bore for machine bolt 8.

Component parts 7, 8, and 9 when assembled in the manner indicated constitute the lower cable or flexible member fitting. 25

It will be noted from the above description and with reference to the accompanying sheets of drawings that the lower cable or flexible member fitting, by means of grooved pulley 8, provides a movable bearing or support for itself by its contact with the top surface of the cable or flexible member 6, at its lower loop thereby enabling the lower loop of the cable or flexible member 6, to assume any required angle between a horizontal and vertical plane, permitting it thereby 35 to automatically align itself with the upper loop of the cable or flexible member 6.

It will also be noted that the threaded shank of the component part 1 of the lower cable or flexible member fitting permits of a swivel movement in a horizontal plane between itself and turnbuckle 10, thereby enabling the grooved pulley 9 to likewise swivel and to automatically align the upper and lower loops of the cable or flexible member 6, regardless of whether the ceiling or 45 supporting superstructure fittings 2, are located in the same vertical plane with the center line of the monorail trackage 14 as shown, or alternately off-set therefrom as previously noted.

Fittings indicated by numerals 10, 11, 12, and 13 when assembled provide a rigid connection between the lower cable or flexible member fitting and the monorail trackage section 14, with provision thereon for vertical adjustment independent of that made possible by the inherent flexibility and continuity of the cable or flexible member 6. 50

It will be noted from the foregoing description and with reference to the accompanying sheets of drawings, that owing to the inherent flexibility 60 and possible continuity of the cable or flexible member 6, used in connection with the upper and lower cable or flexible member fittings as set forth, many useful and desirable arrangements of monorail trackage suspension are available with my flexible member suspension for monorail trackage. Although I have shown and described, and subsequently claimed herein, a flexible cable, I do not wish to be limited to the same as any similar flexible member, such as a wire, chain, or the like, may be used in the same manner. 65

While I have described and illustrated my flexible member suspension for monorail trackage as applied to a T-bar section, utilized in this in- 70 75

stance as a monorail trackage section, it should be understood that I do not intend to limit its use or application to the monorail trackage section illustrated and described but to extend its 5 use and application to all monorail trackages previously referred to.

It should be likewise understood that I do not confine myself to the precise details of construction of the fittings described and illustrated, but 10 regard my invention as including such changes and modifications to the fittings described and illustrated as may be necessary to adapt my flexible member suspension for monorail trackage to such monorail trackage sections previously referred to as do not involve a departure from the 15 spirit of the invention and the scope of the appended claims.

Having thus described my invention, I claim:

1. In a track hanger, the combination of a 20 fixed overhead superstructure, a monorail trackage, and a continuous flexible cable, with a series of primary upper fittings with provision thereon for establishing a universal connection between the fixed overhead superstructure and said cable, 25 and a series of secondary lower fittings with provision thereon for establishing connection between said cable and monorail trackage, said primary upper and secondary lower fittings connecting alternately in sequence with the cable, 30 and permitting free movement of said cable therethrough.

2. In a track hanger, the combination of a 35 fixed superstructure, a monorail trackage, and a continuous flexible cable, with a series of primary upper fittings with provision thereon for an adjustable, lockable and universally swivable connection between said cable and supporting superstructure, and a series of secondary lower fittings with provision thereon for a slideable and 40 vertically adjustable connection between said cable and the monorail trackage, said primary upper and secondary lower fittings connecting alternately in sequence with the cable, and permitting free movement of said cable 45 therethrough.

3. In a track hanger, the combination of a 50 superstructure and a monorail trackage, a continuous flexible cable therebetween, alternately and operatively connected with said superstructure and trackage for supporting the trackage to the superstructure, whereby the preliminary vertical adjustment of the trackage is obtained, 55 said cable connections permitting free movement of the cable for said preliminary vertical adjustment.

4. A track hanger having a superstructure and trackage, a flexible connection adapted to be placed between the superstructure and trackage, to support the trackage to the superstructure, 60 comprising a plurality of superstructure fittings, a plurality of trackage fittings, and a flexible member alternately and operatively connected with said fittings, the connections being such as to permit the cable to pass freely in respect 65 thereto, whereby upon the pulling of one or the other end or both ends of said flexible member or the release thereof, the distance between the superstructure and trackage is varied.

5. A track hanger having a superstructure and 70 trackage, a flexible connection adapted to be placed between the superstructure and trackage, to support the trackage to the superstructure, comprising a plurality of guides adapted to be fastened to the superstructure, a plurality of second guides adapted to be fastened to the track-

age, locking means for one of said plurality of guides, and a flexible cable passing through all of 5 said guides, alternately and operatively connected therewith, the guides being such as to permit the cable to pass freely in respect thereto, whereby, upon the pulling of one end of said cable or releasing the same, the distance between the superstructure and trackage may be varied.

6. A track hanger having a superstructure and trackage, a flexible connection adapted to be 10 placed between the superstructure and trackage, to support the trackage to the superstructure, comprising a plurality of guides adapted to be fastened to the superstructure, a plurality of second guides adapted to be fastened to the trackage, 15 locking means for said first-mentioned guides, a flexible cable passing through all of said guides and alternately and operatively connected therewith, the guides being such as to permit the cable to pass freely in respect thereto, 20 whereby, upon the pulling of one end of said cable or the release of the same, the distance between the superstructure and the trackage may be varied, and a universal connection for said first-mentioned guides adapted to be fastened 25 to the superstructure.

7. A track hanger having a superstructure and trackage, a flexible connection adapted to be placed between the superstructure and trackage, to support the trackage to the superstructure, 30 comprising a plurality of guides adapted to be fastened to the superstructure, a plurality of second guides adapted to be fastened to the trackage, locking means for one of said plurality 35 of guides, a flexible member passing through all of said guides, alternately and operatively connected therewith, said guides permitting free movement of the flexible member in respect thereto, whereby, upon the pulling of one end of 40 said flexible member or its release, the distance between the superstructure and trackage may be varied, and adjusting means for said second plurality of guides, to vary the distance of said guides from said trackage.

8. A track hanger having a superstructure and 45 trackage, a flexible connection adapted to be placed between the superstructure and trackage, to support the trackage to the superstructure, comprising a plurality of universal joint connections 50 adapted to be fastened to the superstructure, a plurality of guides supported by said universal joint connections, a second plurality of guides, means connecting said second plurality of guides with the trackage, means adjusting the distance between said second plurality of guides 55 and the trackage, said last named guides permitting said connections to be laterally displaced, a cable passing through both pluralities of guides alternately, said guides permitting free movement of the cable in respect thereto, and means 60 upon at least one plurality of guides for locking the cable.

9. In a track hanger, the combination of a 65 fixed superstructure, a trackage and means for suspending the trackage to the superstructure, said means being connected with the superstructure alternately at opposite sides of the line of the trackage, and being free to move in respect to the superstructure and trackage, whereby, upon the pulling of one end of the means or the 70 release of the same, the distance between the superstructure and trackage may be varied.

10. In a track hanger, the combination of a 75 fixed superstructure, a trackage and means for suspending the trackage to the superstructure,

- 5 said means permitting the trackage to be movable three dimensionally either longitudinally or transversely or vertically thereto, or in resultants thereof, and said means being free to move in
5 respect to the superstructure and trackage, whereby, upon the pulling of one end of said means or the release of the same, the distance between the superstructure and trackage may be varied.
- 10 11. A track hanger having a superstructure and trackage, a flexible connection adapted to be placed between the superstructure and trackage, to support the trackage to the superstruc-

ture, comprising a plurality of guides adapted to be fastened to the superstructure, a plurality of second guides adapted to be fastened to the trackage, locking means for one of said plurality of guides, a flexible cable passing through both 5 series of guides, and alternately and operatively connected therewith, said cable being freely movable in respect to said guides to permit the pulling in or letting out of the cable, or to raise or lower the track, and a horizontal swivel connection between the second series of guides and said trackage.

RUSSELL E. NELLES.
